Howard v. Smith

UNITED STATES PATENT OFFICE.

JAMES F. LOCKWOOD, OF PHILADELPHIA, PENNSYLVANIA.

DESIGN FOR A TRAY.

SPECIFICATION forming part of Design No. 16,191, dated August 4, 1885.

Application filed May 18, 1885. Term of patent 3½ years.

To all whom it may concern:

Be it known that I, JAMES F. LOCKWOOD, a citizen of the United States, and a resident of Philadelphia, Pennsylvania, have invented a certain new and original Design for a Tray, of which the following is a specification.

My design for a tray is fully shown in the accompanying drawings, in which Figure 1 is a perspective view of the tray, and Fig. 2 is a sectional view of the same.

The tray has in the bottom a series of continuous concentric grooves, *a*, and has an outer raised rim comprising the rounded portion *b* and flat top *d*. The flat surface *f* of the bottom of the tray, within and between the grooves *a*, is roughened or indented in imitation of hammered work.

The tray may be either circular or oval in outline, the grooves *a* conforming to the outline of the tray.

I claim—

1. A design for a tray, said design consisting of a tray having a raised rim and a bottom, with continuous concentric grooves *a* and intervening planes *f*, as shown and described. 25

2. A design for a tray, said design consisting of a tray having a raised rim and a bottom, with continuous concentric grooves *a* and intervening planes *f*, having their surfaces indented in imitation of hammering, as shown 30 and described.

In testimony whereof I have signed my name to this specification in the presence of two subscribing witnesses.

JAMES F. LOCKWOOD.

Witnesses:

HENRY BOSSERT,
HARRY SMITH.
